UNITED STATES PATENT OFFICE

123,825

DESIGN FOR A BIRD NEST

Raymond Trilling, Chicago, Ill.

Application November 13, 1939, Serial No. 88,228

Term of patent 7 years

To all whom it may concern:

Be it known that I, Raymond Trilling, a citizen of the United States of America and a resident of Chicago, Cook County, Illinois, have invented a new, original, and ornamental Design for a Bird Nest, of which the following is a specification, reference being had to the accompanying drawing, forming a part thereof.

Figure 1 is a perspective view of the bird nest showing my new design.

Figure 2 is a side elevation of the same. The essential and characteristic feature is shown in full lines in the drawing.

I claim:

The ornamental design for a bird nest, substantially as shown and described.

RAYMOND TRILLING.
